UNITED STATES PATENT OFFICE

2,505,179

APPARATUS FOR SPRAYING
TRAVELING MATERIALS

Wilson R. Gaythwaite, Glasgow, Scotland, assignor to W & J Martin Limited, Glasgow, Scotland, a British company

Application April 23, 1947, Serial No. 743,273
In Great Britain May 2, 1946

3 Claims. (Cl. 91—45)

1

This invention relates to an improved apparatus for spraying travelling materials.

In a number of industrial processes materials are treated with liquids by passing them in the form of a continuous web, or by transporting them on a conveyor belt, through a liquid spray. Fabric lengths, textile piece goods, paper, and miscellaneous articles, may be subjected to processes of the kind for the purpose of dyeing, impregnating, forming films or coatings, and so on. A particularly valuable application of this process is to be found in the treatment of hides and skins in the leather industry, and in particular in the continuous and automatic application of a spray film of finish material to leather.

It is generally desirable in such processes to ensure that all parts of the travelling material receive a uniform application of spray, and it is an object of the invention to provide a machine in which this is achieved.

According to the invention there is provided an apparatus for spraying travelling materials, wherein a liquid sprayer is adapted to be reciprocated across the path of travel of the said materials, and wherein means are provided for controlling the rate of flow from the sprayer in accordance with the instantaneous speed thereof so as to give a substantially uniform delivery of spray over the whole width of the said materials.

Preferably the rate of flow is controlled by a control valve actuating member mounted on the sprayer and co-operating with a fixed cam or template surface.

The sprayer may for example be reciprocated with a substantially simple harmonic motion, and in this case the contour of the cam or template should be substantially a sine curve. A motion of this kind may be imparted to the sprayer by means of a four-bar linkage.

In order that the invention may be well understood, one embodiment thereof will now be described and illustrated with reference to the accompanying drawings, in which:

Fig. 1 is a diagrammatic side view of a machine for the application of a spray film of finish material to leather, with certain of the parts removed.

Fig. 2 is a plan view thereof.

Fig. 3 is a cross-section on the line III—III of Fig. 2.

Fig. 4 is an enlarged detail cross-sectional view on the line IV—IV of Fig. 3.

Fig. 5 is an enlarged cross-sectional view taken on the line III—III of Fig. 2, but in the reverse direction, showing a modified form of cam,

2

Fig. 6 is a diagrammatic elevation of the opposite side from Fig. 1 showing control means for the modified cam system of Fig. 5, and

Fig. 7 is an enlarged detail partial view of a cross-section on the line VII—VII of Fig. 5.

Referring now to the drawings, a continuous moving wire-mesh conveyor belt 1 runs over an idler roller 2 and is driven by a roller 3 which in turn is driven from a motor 4 via a system of belting and reduction pulleys mounted on counter shafts 5, 6. The belt 1 is arranged to move through a spray cabinet 7 and a heating cabinet 8, heated by a steam coil 9. A trough 10 extends below the upper run of the belt and communicates through apertures 11 with an exhaust duct 12. Two pairs of parallel guides 13 extend horizontally across the upper part of the spray cabinet. Brackets 14 are slidably mounted on the guides 13 and carry pivotally mounted spray guns 15. Screws 16, having knurled heads for ease of operation, are provided for angular adjustment of the spray guns in their pivotal mounting. Each gun 15 has a control valve trigger in the form of a cranked lever arm 17 having a forked end carrying a roller 18 which co-operates with a fixed cam 19 extending across the cabinet parallel to the guides 13. A crank pin 20 on a disc pulley 21, which is mounted on the countershaft 6, is linked by means of a connecting rod 22 to a lever 23 pivotally mounted at 24 on the base of the machine so as to form a four-bar linkage. A cross-piece 25 is provided on the lever 23 and is arranged to move over arcuate guides 26 so as to guide the lever 23 in its oscillation. An endless leather belt 27 is connected to the cross-piece 25 and to the spray gun brackets 14 and runs around four guide rollers 28. A distributor head 29 is mounted for rotation about a vertical axis in a ball bearing 30 in the uppermost part of the spray cabinet. Flexible pipes 31, 32 supply compressed air and finishing liquid respectively to the distributor head. Flexible pipes 33, 33a convey compressed air and finishing liquid respectively from the distributor head 29 to the guns 15.

In operation, the conveyor belt feeds skins slowly first through the spray cabinet and then through the drying cabinet. The skins are sprayed in the spray cabinet and excess spray fumes are continuously exhausted through the trough and exhaust duct below the conveyor belt. The skins then pass below the steam coil in the heating cabinet and are dried. The rotary motion of the crank pin 21 is transformed by the four-bar linkage into a substantially simple har-

monic motion of the lever 23, which is transmitted by the endless belt 27 to the spray guns 18 to reciprocate them across the direction of motion of the conveyor belt. The rollers 18 ride up and down on the cam surface, rising in the middle of the stroke and falling at the end of the stroke. The valve actuated by each trigger arm 17 is thus opened most widely whilst the sprayer is moving at its fastest in the middle of its stroke, and are momentarily closed at the end of each stroke when the sprayer is momentarily stationary.

In order to adjust the device so that the valve only just closes at the end of the stroke, each gun 15 may be adjusted by means of the screw 16 to rock it about its pivotal mounting.

In the modification shown in Figures 5 to 7, an adjustable cam 19a is provided instead of the fixed cam. This cam is in the form of an eccentrically turned rod which may be rotated to vary the lift which it exerts on the cam follower roller 18. The cam is shown in Figures 5 and 7 in the maximum lift position, in which it presents a sine curve of maximum amplitude to the cam follower. As the cam is rotated the contour presented is a sine curve of decreasing amplitude, until after rotation through 180° the amplitude has become zero and a long flat is presented to the cam follower.

The position of the cam may be adjusted by means of the hand wheel 34. Arms 35 are mounted on the shafts of the cam 19a and are secured by means of set screws 36. The two arms 35 are linked by a connecting rod 37, which extends to the delivery end of the machine, where it is connected to a rack and pinion device 38 operated by a hand wheel 39. Rotation of the hand wheel 39 causes the connecting rod 37 to move and the arms 35 to turn, altering the setting of the cams 19a. Control may conveniently be exercised by an operator who also takes the finished skins off the machine.

Fig. 6 also shows an arrangement for washing the conveyor belt to remove any finishing liquid before a fresh pass through the spray cabinet. This arrangement consists of an extension pipe 40 carrying the condensate from the steam heating coil via a steam trap 41 to an orifice 42 where the hot condensate water is delivered on to the lower run of the conveyor belt. The water is then collected in the tray 43 and evacuated through the waste pipe 44.

I claim:

1. Apparatus for spraying travelling materials comprising an endless conveyor belt for transporting said materials, two liquid-sprayers slidably mounted for reciprocation in opposite directions in mutually parallel paths above and across the path of travel of said materials, a rotary driving shaft for said belt, a four-bar linkage operatively connected to said driving shaft, an endless band running over a plurality of guide-rollers and connected to said linkage and to said liquid-sprayers, drive-means for transmitting a substantially simple harmonic reciprocating motion to said liquid-sprayers through said band, a separate control valve incorporated in each said liquid-sprayers, a separate member for actuating each said control valve, and a separate cam rail in cooperation with each said member, each said member having a follower in contact with said cam-rail and arranged to travel to-and-fro

along a surface of the said respective cam rail which latter is contoured substantially as a sine curve so as to vary the rate of flow from said liquid-sprayers in accordance with the instantaneous speed thereof so as to give a substantially uniform delivery of spray over the whole width of said materials.

2. Apparatus for spraying travelling materials comprising a liquid-sprayer mounted for reciprocating movement, means for conveying said materials beneath said liquid-sprayer, means for reciprocating said liquid-sprayer across the path of travel of said materials, a control valve incorporated in said liquid-sprayer, a valve-actuating member having a cam follower and operable to vary the opening of said control valve, a cam rail having a plurality of different cam-profiles and angularly adjustable about its axis to present to said valve-actuating member follower a series of different cam profiles having different lifts, the follower of said valve-actuating member being in contact with and adapted to travel along and co-operate with the cam profile presented thereto to vary the opening of the said control-valve in accordance with the instantaneous speed of said liquid-sprayer, each of said different cam profiles being adapted when presented to said valve-actuating member to give a different maximum opening of said control valve.

3. Apparatus for spraying travelling materials comprising an endless conveyor belt for transporting said materials, two liquid-sprayers slidably mounted for reciprocation in opposite directions in mutually parallel paths above and across the path of travel of said materials, a rotary driving shaft for said belt, a four-bar linkage operatively connected to said driving shaft, an endless band running over a plurality of vertical guide-rollers connected to said linkage and to said liquid-sprayers so as to transmit a substantially simple harmonic reciprocating motion to said liquid-sprayers, a separate control valve incorporated in each said liquid-sprayer, a separate valve-actuating member operable to vary the opening of each said control valve, a follower connected with each said valve-actuating member, a cam rail having a plurality of different cam-profiles and angularly adjustable about its axis to present to the follower of said valve-actuating member a series of different cam profiles having different lifts, each said valve-actuating member follower being in contact with said cam rail and adapted to travel along and co-operate with the cam profile presented thereto to vary the opening of its said respective control-valve in accordance with the instantaneous speed of its said respective liquid-sprayer, each of said different cam profiles being adapted when presented to said respective valve-actuating member to give a different maximum opening to said respective control valve.

WILSON R. GAYTHWAITE.
